US00D997610S

(12) **United States Design Patent** (10) **Patent No.:** **US D997,610 S**
(45) **Date of Patent:** **** Sep. 5, 2023**

(54) **DISPLAY STRUCTURE GROUP**

(71) Applicant: **Apple Inc.**, Cupertino, CA (US)

(72) Inventors: **Federico F. Tio**, Santa Cruz, CA (US); **Frank Craig Thaler**, Santa Cruz, CA (US); **Wesley B. Hamm**, San Francisco, CA (US); **Kevin Fenton Smeds**, San Francisco, CA (US); **Russell John Kaaihue Heirakuji**, Cupertino, CA (US)

(73) Assignee: **Apple Inc.**, Cupertino, CA (US)

(**) Term: **15 Years**

(21) Appl. No.: **29/848,832**

(22) Filed: **Aug. 5, 2022**

(57) **CLAIM**

The ornamental design for a display structure group, as shown and described.

DESCRIPTION

FIG. 1 is a top front perspective view of a display structure group showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a top front perspective view of another embodiment of a display structure group showing the claimed design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines in the figures show portions of the display structure group that form no part of the claimed design.

1 Claim, 8 Drawing Sheets

Related U.S. Application Data

continuation of application No. 29/499,677, filed on Aug. 18, 2014, now Pat. No. Des. 734,965, which is a continuation of application No. 29/432,724, filed on Sep. 19, 2012, now Pat. No. Des. 713,658.
